UNITED STATES PATENT OFFICE.

THOMAS BAILEY, OF NEW YORK, N. Y.

FIREPROOF-BUILDING CONSTRUCTION.

SPECIFICATION forming part of Letters Patent No. 576,713, dated February 9, 1897.

Application filed May 8, 1896. Serial No. 590,667. (No model.)

To all whom it may concern:

Be it known that I, THOMAS BAILEY, a citizen of the United States, and a resident of New York city, in the county and State of New York, have invented certain new and useful Improvements in Fireproof-Building Construction, of which the following is a specification.

My invention consists of improvements in construction of the parts of metallic-frame structures whereby substantial buildings of moderate height may be erected on foundations of less expensive structure than ordinarily found necessary and without bolting or riveting the parts together in the erection, whereby much time and expense can be saved and the buildings can be taken down for removal and erection elsewhere when desired, as hereinafter described, reference being made 20 to the accompanying drawings, in which—

Figure 1 is a perspective view of parts of two sides of a building constructed in accordance with my invention with hollow-brick inclosing material. Fig. 2 is a plan of a tie-plate used in the brick inclosing wall. Fig. 3 is an inside elevation of part of a side of a building of like construction with dovetail sheet-metal and plaster inclosing material, one of the sills being sectioned transversely 30 and some other parts being also sectioned. Fig. 4 is a plan of part of one of the horizontal ties seen in side view in Fig. 3. Fig. 5 is a plan view of the base or foundation and corner-posts for a building of small size. Fig. 6 is a detail in vertical section on line 22, Fig. 7. Fig. 7 is a plan of parts of two sides of a building with fire-brick siding. Fig. 8 is a plan of parts of two sides with dovetail corrugated sheet-metal and plaster siding. Fig. 9 is a 40 detail in section on line 33, Fig. 5. Fig. 10 is a section on line 44, Fig. 9. Fig. 11 is a plan view of a portion of a floor and ceiling structure. Fig. 12 is a transverse section of a portion of a floor and ceiling structure. Fig. 45 13 is a perspective view of a cross-bar used to support the filling between the beams.

For the sills *a* I take rolled-metal beams of approved shapes, preferably I-beams, but other shapes may be used, and, having first 50 suitably prepared them for being connected together and for reception of the posts and studding, lay them flatwise in trenches of ap-

proved depth in the ground, with or without concrete or other suitable bedding, where the nature of the soil requires it, using sills of 55 greater lengths than the required lengths of the sides of the structure and placing the transverse sills crosswise upon the others in the lines or planes of the sides of the superstructure, with the edges of the flanges of the 60 upper sills resting on the edges of the flanges of the lower sills and with the end portions of the sills projecting beyond the lines of the superstructure, as shown at *b*, the purpose of these extensions being to afford anchorage 65 for resisting wind-pressure and for maintaining the upright position when the soil may be washed out at one side, as frequently happens in the case of buildings built on the sea-shore. In the said previous preparation of 70 the sills I perforate the webs *d*, as at *e*, to receive tenons *f* of the corner-posts *g* where the sills cross each other, and I provide metallic blocks *h* to fill the spaces between the webs *d* of the two sills to distribute the weight to be 75 sustained largely on the webs of the sills. The posts *g* will be produced in hollow form in any approved way, as by two angle-bars arranged to inclose a hollow space, as in Fig. 10, and the tenons *f* will be made with a head 80 *h'* and be inserted and riveted as shown in Fig. 9 or in any other approved way.

The tenons *f* will be secured with keys, as *i*, Figs. 9 and 10; under the web of the lower sill. When posts are required of greater 85 length than is feasible in one section, a socket *j* will be inserted in the upper end of a section, and an upper section, as *g'*, Fig. 3, will be connected therewith by a tenon *k*. These tenons may be keyed in two directions, if desired, for greater strength, as indicated in said Fig. 3.

For connecting the metallic studs *l* to the sills and beams or horizontal tie-bars *m* to the posts I make dovetail perforations *n* or *o* 95 through the webs of the sills or posts and provide dovetail ends *p*, Fig. 4, of said studs or ties that will enter the perforations at their wide sides, but will lock therein when shifted to the narrow sides of said perforations, and 100 insert keys, as *q*, to hold them in the locking positions; but instead of employing separate keys I may provide tongues, as *s*, of the metal partly displaced in making the perforations

o, which, being bent aside to admit the ends p, may be bent back after the admission to lock said inserted ends. Instead of the dovetail form of these perforations and ends it is 5 to be understood that any equivalent form that will interlock against pulling out may be used, and I do not limit myself to the dovetail form shown. The posts may have brackets, as j², for additional support of the horizontal tie-bars m.

In Figs. 1 and 7 I represent the siding as consisting of hollow bricks or tiles t, laid on the sills at the outer sides and inclosing the posts and studs and having rods u, extending vertically through them and the sills and beams to stay the bricks against lateral thrusts, and also having flat tie-plates v between courses at suitable intervals apart, through which the rods also pass for securing 20 lateral stability. The apertures of the bricks in which the rods are inserted will be filled with cement to stiffen the walls.

In Figs. 3 and 8 I represent the siding as consisting of dovetail corrugated metallic 25 sheets w with plaster coating w', which also inclose the posts and studs for protection from heat in case of fire in close proximity.

The sheets are arranged with the ribs and grooves upright, and where the edges of two 30 sheets meet they are confined in the grooves of horizontal I tie-bars, as m, Fig. 3, but when sufficiently wide to reach from sill to beam they may be used in connection with studs l, as in Fig. 8, and may be screwed or 35 riveted to them. In the upright arrangement of these sheets they afford material strength for supporting weight above. This form of siding may be used both inside and outside, as in Fig. 8, and the brick siding may also be 40 so used, if desired.

To carry fireproof filling, as concrete and the like, between the floor-beams a², so as to have wide space between said filling and the ceiling b², I apply cross-bars c² for supporting 45 said filling to the upper flanges of the floor-beams, as shown in Figs. 11 and 12, said cross-bars consisting of inverted-T bars or other angle-bars of suitable form, notched in the ends, as at d², to engage said upper flanges 50 of the beams, with the upper edges reaching a little above the upper edges of the beams and their lower edges a little below, so that with filling supported on flanges e² of the cross-bars and reaching to or a little above 55 the upper edges of the cross-bars, and so as to cover the tops of the beams, the thickness of filling material need not be in excess of what is needed for protection of the beams above, as is the case when the cross-bars c² 60 are supported on the lower flanges of the floor-beams and has the requisite thickness for supporting the floor-boards on top and is correspondingly lighter, and there is larger free space between the ceiling and beam filling 65 for additional protection from fire below.

I suspend the ceiling from the flanges e² of the cross-bars by hangers f² and in this case

represent said ceiling as consisting of dovetail corrugated sheets plastered on the under side and covered with concrete or plaster on 70 the upper side and supported at the edges of the sheets on the flanges of inverted-T bars g², said bars being supported by the hangers f². I also represent the same form of sheets to support the beam-filling, as h², said sheets 75 being supported on the flanges of the inverted-T bars c², but any other suitable sheets or plates or bricks or other fireproof blocks may be used, as represented at i².

The sills and other exposed parts will be 80 covered with any approved protective coating, as asphalt or tar preparations or paint, for protection against corrosion.

It will be seen that all preparations of the parts for erection may be done in the shop, 85 so that they have only to be assembled and put together and keyed in erection, which may be done quickly with economy of time and labor, and such buildings may be readily taken apart and reerected elsewhere. 90

I claim as my invention—

1. In metallic-frame structures for buildings, the sills placed crosswise at the angles of the building one upon another and being prolonged beyond the sides of the building 95 outwardly to form anchorage extensions to oppose wind-pressure, said sills secured at the crossings by tenons of the posts inserted through perforations of the webs of the sills and keyed under the lower sills substantially 100 as described.

2. In metallic-frame structures for buildings, the sills consisting of channel-bars placed crosswise at the angles of the building, with filling-blocks between the webs of 105 the sills and secured at the crossings by tenons of the posts inserted through perforations of the webs of the sills and of the filling-blocks and keyed under the lower sills substantially 110 as described.

3. In fireproof-building construction, the combination with metallic sills placed crosswise one upon another at the crossings, hollow metallic posts and tenons having heads inserted and secured in the ends of the hollow posts, said tenons inserted through the webs of the sills and keyed under the lower sills substantially as described. 115

4. In fireproof-building construction, the combination of metallic sills placed crosswise one upon another at the angles, corner-posts seated on said sills at the crossings and secured by tenons inserted through the webs of the sills and fireproof sidings laid on the outer margins of the sills, said sidings consisting 120 of walls of hollow brick with vertical stay-rods inserted through apertures of the bricks substantially as described. 125

5. In fireproof-building construction, the combination of metallic sills placed one upon 130 another at the angles, posts seated on said sills at the crossings and secured by tenons inserted through the webs of the sills and fireproof sidings laid on the sills, said sidings

consisting of walls of hollow bricks with stay-rods inserted through apertures of the bricks, and stay-plates between courses of bricks at intervals, said plates perforated and the rods inserted through them substantially as described.

6. In fireproof-building construction, the combination with metallic sills and posts of metallic studs and ties having interlocking ends as *p* inserted in interlocking perforations in the webs of the posts or sills and keyed therein substantially as described.

7. In fireproof-building construction the combination with metallic sills and posts, of metallic studs and ties having interlocking ends as *p*, inserted in interlocking perforations as *o*, formed with key-tongues as *s* to lock the said ends in the perforations substantially as described.

8. In fireproof-building construction, hollow metallic sectional posts having joint connections consisting of a socket as *j* inserted and secured in the end of one section, and a tenon as *k* having a head inserted and secured in the end of the other section and adapted for inserting in the socket and for reception of one or more keys below the socket and inserted through the shell of the post substantially as described.

9. In fireproof-floor construction, the floor-beam-filling supporting-bars secured to the upper flanges of the floor-beams and extending both above and below the upper surfaces of said beams, and consisting of inverted angle-bars with the intermediate plates and filling therein carried on the flanges of the angle-bars below the level of the upper surfaces of the beams substantially as described.

10. In fireproof-floor construction, the floor-beam-filling supporting-bars secured to the upper flanges of the floor-beams and extending both above and below the upper surfaces of said beams and consisting of inverted angle-bars, with the intermediate plates and filling thereon carried on the flanges of the bars below the level of the upper surfaces of the beams in combination with the fireproof ceiling suspended from the flanges of said bars and below the lower edges of the beams substantially as described.

Signed at New York city, in the county and State of New York, this 29th day of April, A. D. 1896.

THOMAS BAILEY.
